US0D1078383S

(12) **United States Design Patent** (10) **Patent No.:** **US D1,078,383 S**
(45) **Date of Patent:** **** Jun. 10, 2025**

(54) **CUP**

(71) Applicant: **SHENZHEN E-BON INDUSTRIAL CO., LTD.**, Shenzhen (CN)

(72) Inventor: **Wenguang Zhang**, Shenzhen (CN)

(73) Assignee: **SHENZHEN E-BON INDUSTRIAL CO., LTD.**, Shenzhen (CN)

(**) Term: **15 Years**

(21) Appl. No.: **29/855,017**

(22) Filed: **Sep. 29, 2022**

(51) **LOC (15) Cl.** **07-01**

(52) **U.S. Cl.**

USPC **D7/511**

(58) **Field of Classification Search**

USPC D7/300.1, 608, 509, 511, 510, 523, 591, D7/597, 598, 543, 396.1, 396.2, 300, 605, D7/387, 392.1
